(57) **CLAIM**

The ornamental design for a dental buccal tube, as shown and described.

DESCRIPTION

FIG. 1 is a front right perspective view of the dental buccal tube;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front right perspective view thereof in the change state;

FIG. 9 is a front view thereof in the change state;

FIG. 10 is a rear view thereof in the change state;

FIG. 11 is a left side view thereof in the change state;

FIG. 12 is a right side view thereof in the change state;

FIG. 13 is a top view thereof in the change state; and,

FIG. 14 is a bottom view thereof in the change state.

The dental buccal tube may be used for orthodontic treatment, while the concealable traction hook can be stored and unfolded according to the treatment needs.

The broken line shown in the drawings is included for the purpose of illustrating portions of the dental buccal tube and forms no part of the claimed design.
